UNITED STATES PATENT OFFICE.

WILLIAM MARRETT, OF TOLEDO, OHIO, ASSIGNOR TO THE LIBBEY GLASS COMPANY, OF SAME PLACE.

DESIGN FOR A GLASS DISH.

SPECIFICATION forming part of Design No. 33,910, dated January 15, 1901.

Application filed March 13, 1899. Serial No. 708,972. Term of patent 7 years.

To all whom it may concern:

Be it known that I, WILLIAM MARRETT, a citizen of the United States, residing at Toledo, Lucas county, Ohio, have invented and produced a new and original Design for a Glass Dish, of which the following is a specification.

In the accompanying drawings, made part hereof, Figure 1 is a bottom plan view of a dish or bowl embellished with my design; and Fig. 2 is a cross-sectional view of the dish on line $x x$, Fig. 1.

It will be seen that in the drawings the details are not repeated in the portions which go to make up the harmonious design; but the recurrence of these parts will be fully understood by those skilled in the art without repetition.

In my design there are cut or impressed in the surface to be ornamented eight deep outline-cuts. Four of these, a , each describe approximately a semicircle, each having its two extremities at the margin of the vessel and separated by a quarter of the vessel's circumference, as at a' . There are four of these terminal points a' , each marking the end of two oppositely-curved cuts a . The other four deep outline-cuts b , which are also curved, but do not extend to the margin of the vessel, are disposed in such relation to each other and to the cuts a that the eight cuts at the center of the vessel bound an eight-sided figure c . The outline-cuts also bound four six-sided figures d , equidistantly arranged around the margin of the vessel. Between each adjoining two of the six-sided figures d are smaller

four-sided figures e . The spaces $c d e$ are formed into stellated rosettes. The faces of the remaining areas bounded by the outline-cuts are finished in checker-work or "silver diamond-work," as at f . These checkered spaces are in groups of four and radiate from the rosettes e , each of which rosettes forms a center for such a group. The groups of checkered figures, with their centers e , present the appearance of four-pointed stars, which alternate with the rosettes d around the central figure c . The checkered areas f are divided into diamond-shaped spaces by cuts considerably deeper than the lines forming the checkered work.

The margin of the vessel is indented to form eight approximate segments of circles, which segments are in turn scalloped, as indicated in Fig. 2. Four of these scalloped segments a' lie adjacent to the four six-sided figures d . The other four scalloped segments g , which alternate with the segments a' , are radially cut or impressed in fan-like form. These latter cuts are equidistant ensiform channels f' , alternating with groups of shallower and narrower cuts f'' , as shown.

The distinctive feature of my design is a glass dish bearing the herein-described ornamentation.

What I claim is—

The design for a glass dish, substantially as herein shown and described.

WILLIAM MARRETT.

In presence of—

WILBER A. OWEN,
W. F. DONOVAN.
